UNITED STATES PATENT OFFICE.

HENRY SEIDE, OF NEW YORK, N. Y.

CAP.

SPECIFICATION forming part of Letters Patent No. 787,121, dated April 11, 1905.

Application filed November 17, 1904. Serial No. 233,094.

To all whom it may concern:

Be it known that I, HENRY SEIDE, a subject of the Czar of Russia, and a resident of the city of New York, borough of Manhattan, in the county and State of New York, have invented a new and Improved Cap, of which the following is a full, clear, and exact description.

This invention relates to improvements in caps, particularly of the general type worn by automobilists, bicycle-riders, and the like, the object being to provide a cap so constructed that it may be readily changed to present different colors or textures, thus practically providing a plurality of caps in a single structure.

I will describe a cap embodying my invention and then point out the novel features in the appended claim.

Reference is to be had to the accompanying drawings, forming a part of this specification, in which similar characters of reference indicate corresponding parts in all the figures.

Figure 1 is a perspective view of a cap embodying my invention. Fig. 2 is a sectional view thereof. Fig. 3 is a section similar to Fig. 2, but showing the parts in a different position. Fig. 4 is a side view showing the parts in still another position, and Fig. 5 is a fragmentary view illustrating the manner of securing the parts together.

Referring to the drawings, 1 designates the band of the cap, having the usual vizor 2 and also having connected to it a lining material 3. The cap has three changeable covers or top pieces 4 5 6. The cover 4 may be of rubber, cloth, or similar material, while the other covers are different materials or different colors. When the cover 4 is placed outermost, as indicated in Fig. 2, its front band portion connects with a band-section 7 and its rear portion connects with a band-section 8. These band-sections are open at one side and are designed to be secured together by means of any suitable fastening device, here shown as an eye 9, for engaging with a hook 10. It will be noted that when the rubber or cloth cover 4 is outermost the top or cover 5 will be folded upon itself, one fold being attached to the cover 4, as indicated at 11, while the other end of said cover is attached to a band-section 12. The cover 6 is also folded upon itself and has one of its folds sewed to the cover 4, as indicated at 13, the other portion of said cover being attached to the fixed band-section 14. From the connection 11 of the cover material 5 with the cover 4 a facing-strip 15 extends downward, being of the same color as said cover 4. A similar facing-strip 16 extends downward from the connection 13 to the band-section 7 of the cover 4. It will be noted that the tops or covers 5 and 6 are stitched together at the center, as indicated at 17.

In the operation should it be desired to have the cover 6 outermost the fastening 9 10 is to be released and then the top or cover 4 drawn rearward over the cap, so that its band portion 7 will be at the rear, and the fastenings may be again secured together. At this time of course the faces of the covering 6, which are indicated in Fig. 2 as adjacent to each other, will be open, so that the under side of the upper stretch will be uppermost and corresponding with the upper side of the lower stretch. When it is desired to have the cover 5 outermost, the parts are to be turned from the rear of the cap forward.

Having thus described my invention, I claim as new and desire to secure by Letters Patent—

A cap comprising a body portion, a cover having connection with a fixed band-section at the rear of the cap, a movable band-section attached to the front of said cover, a second cover adapted to fold upon itself, one fold thereof being secured to the first-named cover, a band-section to which the other fold is secured, a third cover also adapted to fold upon itself, one of the folds being secured to the first-named cover, the said second and third coverings being secured together at the center, a fixed band-section to which the other fold is secured, and facing-strips, substantially as shown and described.

In testimony whereof I have signed my name to this specification in the presence of two subscribing witnesses.

HENRY SEIDE.
